UNITED STATES PATENT OFFICE.

LEWIS E. SHIPP, OF KENTON, OHIO.

CAR CONSTRUCTION.

Application filed June 6, 1928. Serial No. 283,437.

This invention relates to improvements in car construction, and more especially to means for operating sliding doors of poultry cars from the inside. For example, a form 5 of poultry car now in common use is provided with a central aisle with vertical tiers of coops on each side thereof. The ends of aisles, extending the entire length of the car, are closed by sliding doors. For protection, the ends of such aisle are ordinarily 10 provided with vertical bars, the sliding doors being mounted on the outer side thereof.

In the form of cars as heretofore used, it has been difficult or impossible to open and 15 close the doors from the inside of the car.

One of the features of my invention is the provision of improved means permitting the attendant inside of the car to open and close such doors at will, thus enabling him 20 to regulate the ventilation while the car is in motion without leaving the inside.

In that form of device embodying the features of my invention shown in the accompanying drawings, Figure 1 is a view in 25 perspective of one end of a railroad box car showing the same as employed for the transportation of poultry, Fig. 2 is view taken as indicated by the line 2 of Fig. 1, Fig. 3 is a view taken as indicated by the line 3 30 of Fig. 2, and Fig. 4 is a view taken as indicated by the line 4 of Fig. 2.

As shown in the drawings, the center part of the body of the car is closed by an upper sliding door 10 and a lower sliding door 11, 35 the former being supported from the upper rail 12 by means of the hook hangers 13, and the lower door being similarly supported from the rail 14 by the hangers 15.

As shown in Fig. 2, 16 indicates the end 40 wall of the car and 17 the end of the central aisle therein, the coops on each side thereof being indicated by 18, 18. The end of the aisle 17 is closed by vertical bars 19, 19 of common construction, the ends of said bars 45 being preferably supported by cross members (not shown), the ends of said cross members being supported by the vertical channels 20, 20.

It will be seen that the vertical bars 19 50 prevent an attendant inside the car from grasping the door 10 or 11. I have provided means, however, by which such door may be opened or closed from the inside. Such means include a horizontal bar 21 55 lying inside of the bars 19 and preferably near the top of the door 10. This bar pro-

jects through a hole 20^a in one of the channels 20 and its outer end is indicated by 21^a is bent outwardly and inserted through a strap 22 attached to the door as by means 60 of the bolts 23, 23. The other end of the bar 21 is bent inwardly as indicated by 21^b and thence upwardly to form a loop 21^c around the guide rod 24. After the loop is formed, the rod is again bent downwardly 65 and inwardly as indicated by 21^d and its end is bent to form the handle 21^e.

To one flange of the channel 20 is pivoted a latch 25 adapted to hook over the portion 21^a of the rod 21 to hold the door in closed 70 position.

In the operation of the device, the latch 25 is raised to release the bar 21^a and by means of the handle 21^e, the rod 21 may be moved back and forth to slide the door, the eye 21^e 75 sliding on the guide rod 24 during such movement.

The lower door is supported and operated in a similar manner and consequently the same need not be described in detail here. 80

While I have shown and described certain embodiments of my invention, it is to be understood that it is capable of many modifications. Changes, therefore, in the construction and arrangement may be made without departing from the spirit and scope of the invention disclosed in the appended claims, in which it is my intention to claim all novelty in my invention as broadly as possible in view of the prior art. 90

What I claim as new, and desire to secure by Letters Patent, is:

1. In combination with a car having a central aisle closed by vertical guard bars with a sliding door on the outside thereof, means for sliding said door from the inside of the car, said means including a horizontal operating bar lying inside of said guard bars and extending substantially the width of said aisle, one end of said bar extending beyond said guard bars and bent outwardly with its outer end attached to said door, the other end of said operating bar being provided with a handle. 95

2. In combination with a car having a central aisle closed by vertical guard bars with a sliding door on the outside thereof, means for sliding said door from the inside of the car, said means including a horizontal operating bar lying inside of said guard bars 100 and extending substantially the width of the said aisle, one end of said bar extending be- 110

yond said guard bars and bent outwardly with its outer end attached to said door, the other end of said operating bar being provided with a handle, and means for slidably supporting the handle end of said operating bar.

3. In combination with a car having a central aisle closed by vertical guard bars with a sliding door on the outside thereof, means for sliding said door from the inside of the car, said means including a horizontal operating bar lying inside of said guard bars and extending substantially the width

of said aisle, one end of said bar extending beyond said guard bars and bent outwardly with its outer end attached to said door, the other end of said operating bar being provided with a handle, and means for slidably supporting the handle end of said operating bar, said means including a horizontal guide rod and an eye attached to the handle end of the operating rod and embracing said guide rod.

In witness whereof, I have hereunto set my hand this 26th day of May, 1928.

LEWIS E. SHIPP.
